UNITED STATES PATENT OFFICE.

HAROLD T. PAYNE, OF SACRAMENTO, CALIFORNIA.

DOLL.

Application filed October 27, 1925. Serial No. 65,196.

The present invention relates generally to improvements in toy figures, and more particularly to improvements in dolls.

The invention proposes to combine with a portion of a toy figure, such as the head of an ordinary doll, the distinguishing facial characteristics of a plurality of different dolls.

The invention further proposes to adapt the multi-faced head for adjustment upon the body so that the doll as a whole may be readily converted from one type to another by adjusting the head and causing a face thereof to aline with the front of the body of the doll.

The invention further proposes to permit the display of the several faces of the doll one at a time by providing a specially constructed mask or housing for the head.

It is still further proposed to effect the substitution of one face for another by means of a mechanism completely hidden from view and manually operable from the exterior of the doll.

The above and other objects are accomplished by instrumentalities pointed out in the following specification.

The invention is clearly defined in the claims.

A satisfactory embodiment of the invention is illustrated in the accompanying drawings forming part of the specification and in which—

Figure 1 is a view showing the body of a doll in vertical cross section and my invention applied thereto.

Figure 2 is a transverse section on the line 2—2 of Figure 1, looking in the direction of the arrows.

Figure 3 is a rear elevation of the upper portion of the doll shown in Figure 1 with the hair covering removed, and

Figure 4 is a front elevation of the upper portion of the doll of this invention with one of the faces thereof exposed.

In the drawings *a* indicates an ordinary doll body, *b* the head, *c* and *d* fragments of the limbs.

In carrying out my invention I arrange a support 5 wholly within the body *a* and preferably at a point between the upper and lower limbs *c* and *d*. In the upper end of the body I provide a bearing 6 which may be in the form of a bushing extending through an opening in the upper end wall 7 of the body and provided at its outer end

with a head 8 to bear on the plate 7 and secured by a nut 9 screwed upon its inner end. The bearing 6 alines with a bearing 10 in the support 5, and a shaft 11 with one end portion projecting outwardly beyond the bearing 6 extends through the latter and into the body *a* and is journaled in the bearing 10. As shown, the shaft 11 is disposed within the axis of the body *a* and its projecting outer end portion extends through the axis of the head *b*, the outer extremity of the shaft being journaled in a bearing 12 located at the central portion of the inner face of an inverted bowl-shaped base 13 of a housing indicated generally by *e*. The projecting end portion of shaft 11 is fixedly secured against rotation within the head, and the base portion 13 of the housing surrounds the upper portion of the head above the face, and in this position the base is supported by a standard 14, one end of which is fixedly secured to the base 13 and its opposite end secured in any preferred manner, as indicated by 14' to the middle portion of the back of body *a*.

The portion of the standard extending beyond the upper end of body *a* is curved to conform to the figuration of the back of the head of an ordinary doll, and the curvature of the base which forms a continuation of the curvature of the standard also conforms to the contour of the top of the head of an ordinary doll. In addition to the base 13, the housing *e* includes a head covering 90 which may be of hair 15 secured to a lining 16 which in turn is secured in any preferred manner as by an adhesive to the base 13, the lining 15 and hair 16 being constructed so as to provide an observation opening in vertical alinement with the front portion of the body and through which may be viewed the face of the doll. As shown in Figure 1, the head *b* of the doll is formed with a plurality of characteristically different faces 17. The faces may be arranged adjacent or opposite one another, depending upon the construction of the head and the number of faces employed. The area of each of the faces 17 is such as to nicely fit 105 behind the observation opening afforded by the hair so that no more than one face is visible at a time through said opening. The head *b* may be formed of any materials now employed in the manufacture of heads for dolls, and since these items are invariably formed in a mold, it is obvious that the head

of the present invention may also be readily molded within a mold constructed so as to impart faces of different characteristics to the head.

5 In the form shown in Figure 1, two of the faces 17 are employed, the shaded face on the right of the figure being different from that on the left so that when the head is turned for one-half revolution by imparting 10 a corresponding turning movement to the shaft 11, the face on the left turns away from the observation opening and, at the same time, the face on the right is substituted in the said opening. Suitable mechanism is employed for turning the shaft 11. In the present instance I have shown a rack 18 and a pinion 19 for oscillating the shaft 11 through an arc of 180 degrees, the pinion 19 being rigidly secured to the shaft 11 and 15 the rack 18 being disposed in a channeled guide 20 secured to the support 5 so that the teeth thereof will mesh with the teeth of the pinion.

20 To facilitate the operation of the rack, 25 the same is made of a length so that the opposite ends thereof will extend through oppositely disposed recesses in the body *a* and project beyond opposite side portions of the body, as indicated by 21, and stop pins 22 30 are secured to the opposite end portions of the rack and operate to limit the movement of the rack in either direction by moving into contact with the ends of the guide 20.

When it is desired that the turning movement of the shaft be limited to an arc of 180 degrees in either direction, the pins 22 are set so as to alternately abut the guide in each reciprocation of the rack at the time to 35 avoid overthrow of the shaft. It is, of course, to be understood that the degree of turning movement of the shaft may be varied where more than two of the faces 17 are employed.

40 When the toy is in use the projecting end portions 21 of the rack are concealed beneath the apparel usually covering the body

of the doll so that the user of the toy, upon locating with the fingers of the hand the projecting end portions 21 may readily operate the rack to effect the turning of the 50 head.

55 Although I have shown and described one embodiment of my invention, it is to be understood that the same is susceptible of various changes; and I reserve the right to employ such as may come within the scope of the appended claims.

I claim:

1. A doll comprising a body portion having lateral openings, a head superimposed upon the body portion, a shaft disposed longitudinally of the body and fixedly secured to the head, members secured to the opposite end portions of the body and providing bearings for the shaft, a toothed pinion secured to the shaft, a rack engaging the teeth of the pinion and disposed transversely of the body and having its opposite end portions disposed in the openings of the body and projecting beyond opposite side portions thereof whereby the rack may be manipulated to reciprocate and thereby oscillate the head. 70

2. A doll comprising a hollow body portion having lateral openings adjacent one end portion thereof, a head superimposed upon the opposite end portion of the body, a shaft disposed axially of the body and fixedly secured to the head, members secured to the opposite end portions of the body and providing bearings for the shaft, a toothed pinion secured to the shaft, a guide on one of said bearing members, a rack engaging the teeth of the pinion and disposed transversely of the body and slidably fitted in the 75 guide, the opposite end portions of said rack being disposed in the openings of the body and projecting therebeyond whereby the rack may be manipulated to reciprocate and thereby oscillate the head. 80

HAROLD T. PAYNE.
